UNITED STATES PATENT OFFICE

2,637,862

BUOYANT CHAMBER SCUTTLING DEVICE

Raymond L. Freas, Conshohocken, Pa.

Original application June 18, 1948, Serial No. 33,835, now Patent No. 2,593,432, dated April 22, 1952. Divided and this application February 21, 1951, Serial No. 212,182

2 Claims. (Cl. 9—8)

(Granted under Title 35, U. S. Code (1952),
sec. 266)

1

The invention described herein may be manufactured and used by or for the Government of the United States of America for governmental purposes without the payment of any royalties thereon or therefor.

This is a division of my pending application Serial No. 33,835, filed June 18, 1948, directed to Automatically Operated Signalling Apparatus, patented April 16, 1952, Number 2,593,432.

The present invention is directed to the art 10 of scuttling buoyant vessels, and it comprises a device which causes a floating vessel to sink.

The invention is embodied in the Automatically Operated Signalling Apparatus of the above referred to parent application, which is particularly adapted to be deposited on the surface of a body of water by an aviator to send signals which enable the aviator to check his course and determine his location. The signals of the apparatus are useful only until the aviator has checked his course and determined his location.

When the signals from the apparatus have served their purpose, the apparatus can be reclaimed in any suitable manner. However, this is usually not worth the time and danger that may be involved under circumstances expected to prevail when the apparatus is used. Accordingly, it is preferred to consider the signalling apparatus expendable. It is desired that the apparatus discontinue sending signals after it has served its useful purpose, and also that the apparatus destroy itself so that it is no longer a potential source of useful information to an enemy or other unauthorized person.

To accomplish the purposes outlined above, the apparatus of the parent application is equipped with a scuttling device, by means of which it becomes waterlogged after a predetermined time in use, and by means of which it sinks to the bottom of the body of water where it is positioned for use. The present application is directed divisionally to the self-scuttling device of the parent application.

For understanding the principles of the present invention, and for a disclosure of one practical embodiment thereof, attention is directed to the accompanying drawing, in which

Fig. 1 illustrates apparatus embodying the invention in elevation, and

Fig. 2 is a fragmentary cross-sectional elevation of the apparatus of Fig. 1, illustrating the device of the present application in detail.

The apparatus of Fig. 1 is adapted to send radio-frequency signals, and for the purpose is positioned to float on a body of water where it

operates automatically in a manner fully described in the above referred to parent application. The apparatus comprises a buoyancy chamber 15 at one end, a ballast mass 16 at the other end, and a rigid connection 17 between the buoyancy chamber and the ballast mass. The ballast mass 16 submerges because of its weight, and is therefore suspended downwardly from the buoyancy chamber 15 as shown.

As described more fully in the parent application, the rigid connection 17 contains the antenna 18 of the transmitter in collapsed condition until it is put into use, and therefore the connection 17 is a length of tubing as seen in Fig. 2. The antenna is erected automatically by the transmitter being deposited on a body of water for use, and then projects upwardly out of the end of the tube 17, as seen in Fig. 1.

The buoyancy chamber 15 is a container which is preferably of metal and comprises the lid 20, which is screw-threaded onto the container 15 and is additionally secured thereto by soldering or the like means to seal the lid onto the container watertight.

The lid 20 comprises the centrally located bushing 21, which is threaded to receive the gland nut 22 providing a cavity for any suitable packing 23. The bushing 21, gland nut 22 and packing 23 provide a watertight attachment of the buoyancy chamber 15 at its one end to the tube 17.

The sleeve 25 is screw-threaded onto the end of tube 17, the lock nut 26 being provided to secure the attachment. The tube 17, with the sleeve 25 attached at its end, extends lengthwise through buoyancy chamber 15 from the lid 20 and its bushing 21 towards the opposite end where sleeve 25 projects through the end wall of container 15 to the exterior thereof. The internal and external clamping discs 27 and 28 are threaded onto the sleeve 25 respectively inside and outside the buoyancy chamber 15, and are driven towards each other along the sleeve to press opposed to each other against opposite faces of the chamber wall, the gaskets 29 being included in the connection to make it watertight.

The cap 30 encloses the antenna 18 in the tube 17 when the transmitter is not in use, and releases the antenna for its erection and use when the transmitter enters the water for use. This is more fully described in the parent application, and is unimportant for understanding the invention to which the present application is directed.

Electrical leads 33 connect the power pack,

which is embodied in the ballast mass 16, with the transmitting component, which is housed in the buoyancy chamber 15. This is also more fully disclosed in the parent application. For the purpose of the present disclosure it is only important to know that the leads 33 enter the buoyancy chamber through the grommet 34 of rubber or the like material that makes the lead entrance watertight.

The plug 35, also of rubber or the like material, closes an opening watertight through which a tool may be inserted into the buoyancy chamber to adjust the transmitter component in a manner more fully described in the parent application.

The buoyancy chamber 15 is thus a fluid tight container excepting for the scuttling device illustrated generally at 40, and the vent illustrated generally at 41, which constitute the important elements of the invention to which the present application is directed.

The vent 41 operates to maintain the buoyancy chamber at atmospheric pressure, and comprises a nipple 42 which is attached to buoyancy chamber 15 at its upper end by means of the gasket or grommet 43 of rubber or the like material. The lengthwise bore 44 of the nipple 42 extends from the end of the nipple inboard of the buoyancy chamber 15 towards the outboard end where it communicates with the outside atmosphere through the lateral bore or duct 45.

The cap 46 is secured to the outboard end of the nipple 41 and comprises the annular shield or apron 47 which extends downwardly to cover the port of lateral bore 45 and is spaced away therefrom to form an annular channel 48 through which fluid may flow into and out of the passage of bores 44 and 45. The structure permits free air flow into or out of the buoyancy chamber 15. The apron 47 forms a trap that avoids excessive water flow into the buoyancy chamber 15 through the passage of bores 44 and 45, and prevents solids that are floating in the water from closing the port of the lateral bore 45. The cup 50 is pressed into position over the inboard end of the gasket 43. The base of cup 50 is crowned as shown, and the hole 51 at the apex of the crown permits the passage of air. The crown forms an annular trough 52 in which water entering bores 45 and 44 accumulates and is contained to prevent the water from entering the space within buoyancy chamber 15 that houses the transmitting component of the signalling apparatus which it might damage.

The scuttling device 49 comprises a nipple 55 which is secured to the buoyancy chamber by means of the gasket or grommet 56 of rubber or the like material. A lengthwise bore 57 extends from the end of the nipple 55 inboard of the buoyancy chamber 15 towards the outboard end where it communicates with the lateral bore 58. The cap 59 is secured to the nipple at its outboard end, and comprises the annular apron 60 which extends through the wall thickness of buoyancy chamber 15, and around the nipple to cover the port of the lateral bore 58, being spaced away from the port to form an annular channel 61 through which water flows into the passage of bores 58 and 57. The apron 60 forms a trap that prevents solids from entering the passage of bores 58 and 57 and clogging it.

The nipple 55 is through the lid 20, and thus is positioned along the bottom surface of the buoyancy chamber 15 when the signalling ap-

paratus floats on the water in operating position illustrated in Fig. 1. The nipple 55 is therefore submerged, and it provides a passage for water to enter the buoyancy chamber 15 from the time the transmitter starts sending signals.

The cup 64 is secured and sealed to the inboard surface of the lid 20 by soldering or the like means to comprise a container, and it encloses the nipple 55 and the inboard end of its passage 57. A second cup 65 is similarly secured and sealed to the first cup 64 at its end to comprise a second container in series which is more remote from the lid 20, and in the disclosed embodiment a third cup 66 is secured and sealed to the second cup 65 in a similar manner to comprise a third container in series which is more remote from lid 20 than container 65. The cups 64, 65 and 66 preferably are alike, and they constitute a series of individual containers which is attached to the buoyancy chamber in a manner for flow of fluid through the containers in series by the end container 64 of the series being secured and sealed to the lid 20 as described.

The uppermost surface 67 of each container 64, 65 and 66 is depressed downwardly to form a basin, and is provided with a hole 68 through which water tends to drain downwardly into the next lower container.

From the time that the transmitter becomes positioned on the surface of the water for use as illustrated in Fig. 1, water enters the buoyancy chamber 15 through the passage of bores 57 and 58 of nipple 55, the passage being constricted for the water to trickle in, the rate of flow being thereby controlled for a predetermined time interval. The water enters the container or chamber of the first cup 64 where the water is confined until cup 64 becomes full. Then the water flows through the hole 68 of cup 64 into the second cup until it becomes full, after which the water enters the third cup 66 until it becomes full. After all the cups 64, 65 and 66 are full, the water enters the space inside the buoyancy chamber 15 through the hole 68 of cup 66. While water enters buoyancy chamber 15 through the nipple 55, air is displaced and driven out of the buoyancy chamber through vent 41. There may be more or less than three cups 64, 65 and 66 shown, the number of cups and their sizes being determined by the desired time delay, and particularly by the length of time that it is desired for signals to be transmitted before water enters the housing of the buoyancy chamber 15 and renders the transmitting component contained therein inoperative.

Thus the process of scuttling begins from the time that the signalling apparatus begins to operate. However, water does not enter the space within the buoyancy chamber 15 that houses the transmitting component until each of the several cups 64, 65 and 66 have become filled in succession. Soon after water gets into the housing of buoyancy chamber 15 it contacts the transmitting component contained therein and signals stops. Meantime, the transmitter continues to sink until it becomes waterlogged and it then sinks below the surface of the water and to the bottom. The apparatus is thus self-destroying.

The disclosure presents one practical embodiment of the invention, which is not limited to the specific structure shown. The scope of the invention is determined by the accompanying claims.

I claim:

1. In an enclosed buoyancy chamber, a scuttling device comprising a plurality of fluid containers secured and sealed to each other in series, the series of containers being attached to the buoyancy chamber below the water line by an end container of the series being secured and sealed to the chamber, a passage for fluid from the exterior to the interior of the buoyancy chamber comprising a time-delay restricted fluid-passage through the wall of the buoyancy chamber and communicating with the end container of the series that is secured to the buoyancy chamber, the passage also comprising a time-delay restricted fluid-passage through the 15 container at the opposite end of the series and communicating with the exterior of the series of containers, the passage also comprising a time-delay restricted fluid-passage between each of two next-adjacent containers between the opposite end containers of the series, and an air vent in the buoyancy chamber above the water line.

2. In a buoyancy chamber as defined in claim

5
10
15
20

1, the series of containers being attached to the buoyancy chamber on the inside of the chamber, a nipple embodying the fluid-passage through the wall of the buoyancy chamber and comprising a bore through the wall thickness, a second bore communicating with and extending laterally from the first bore exteriorly of the chamber, and an annular channel exteriorly of the nipple and communicating with the second bore outside the buoyancy chamber.
